UNITED STATES PATENT OFFICE

FRANCIS JOHNSON, OF DETROIT, MICHIGAN

MIXING MACHINE

Application filed March 1, 1929. Serial No. 343,588.

The present invention pertains to a novel mixing machine having particular reference to that class of mixing machine which is employed for mixing concrete, cement, powders and the like.

The primary object of the present invention is to devise a mixing machine which has a plurality of separate mixing arms and blades arranged and designed to give a maximum amount of agitation to the cement or the materials to be mixed. The arms and blades are specially designed and have a resiliency which lessens the likelihood of damage thereto while in operation and if any damage should happen to result thereto each arm and blade may be removed separately for repairs or for replacements. The blades carried by the arms, being of a resilient nature, may engage the inner wall of the mixer and the novel arrangement and angularity thereof tends to agitate the substances and to force them toward the door when the arms are rotated, and when the door is open the blades will themselves discharge the mixed substances from the mixer.

A further object of the present invention is to construct a mixing machine provided with the above mentioned features which has a removable or replaceable bottom. The friction of the mixing materials and the blades causes a great deal of wear in the bottom of the mixer and when the bottom is made in a casting it must be made quite heavy with this wear taken into consideration. The expense of the heavy casting is great and the present invention avoids this expense by facilitating the installation of a sheet metal bottom which may be inexpensively formed and which might be replaced several times for the cost of one cast bottom.

With these objects in view and others which are subsidiary thereto or resultant therefrom the present invention is fully disclosed in the following description and the accompanying drawings, in which

Figure 1 is a top plan view of the mixing machine;

Figure 2 is a side elevation of the mixing machine;

Figure 3 is a transverse cross-sectional

view through the mixing machine substantially on the line 3—3 of Figure 2;

Figure 4 is a cross sectional view through one of the blade supporting arms, and

Figure 5 is a cross sectional view through another of the blade supporting arms.

Like characters of reference are employed to designate the corresponding parts throughout.

The numeral 1 designates the end members which are in the nature of supporting legs having outwardly extending flanges 2 near their upper ends, the flanges 2 support bearing members 3 in which the shaft 4 is mounted and to which rotative movement is imparted from the shaft 5 by means of the gears 6 and 7, the shaft 5 being rotated by any suitable power source. The shaft 4 as illustrated, extends from end to end of the mixer and is provided with a squared portion 8 intermediate its ends for a purpose which will later become apparent.

The end members 1 are joined together by a plurality of members adapted to also support the bottom 9 which is semicircular in cross section. The upper edges of the bottom rest against the end joining members 11 and 12, which are bolted to each end as at 13. The member 11 is in the form of an angle iron substantially L-shaped in cross section. The member 12 is substantially L-shaped in cross section and intermediate its ends it is provided with an elongated flange 14 which is cut away at 15 to surround the opening 16 which accommodates the door 17 provided with any suitable latching mechanism. The joining member 18 is in the nature of a channel iron which is slightly concaved to form a seat for the lowermost portion of bottom and support the same, the channel member being joined to the ends 1 by bolts 19.

Side wall members 20 are provided with outwardly extending flanges 21 through which bolts 22 may be passed to secure the members 20 to the joining members 11 and 12 and to the legs 1. The upper edges of the members 20 are inturned as at 23 to prevent the materials from splashing out of the mixer. The ends of the members 20 are provided with flanges 24 which extend outwardly

and to which the end members 25 are secured by bolts 26.

One of the side wall members 20 is provided with an opening 27 in line with the openings 5 15 and 16 to accommodate the door 17. Adjacent the opening 27 there are provided flanges 28 which support a spout 29, the spout being connected to the portion 14 on the member 12 by means of the brackets 30 and 10 the bolts 31. In this manner of construction it is obvious that the bottom member 9 is a separate unit which may quite readily be formed of comparatively thin sheet metal. The weight of the bottom 9 is supported by 15 the channel member 18 and is retained in place by the members 11 and 12 upon which the flanges 21 on the members 20 rest.

In order to remove the bottom member 9, it is sufficient merely to detach the retaining 20 member 11 and the supporting member 18, after which the bottom member will fall from the retaining member 12, although with a slight lateral movement due to the curvature of the member 12. If the positioning of the 25 arms 32 and 33 permits, the bottom member 9 may be withdrawn laterally after removal of the member 11 and without removal of the member 18. Another method of removing the bottom member 9 is to detach one of the 30 end supporting members 1, after which the bottom member may be drawn out in its lengthwise direction.

The square portion 8 of the shaft 4 supports a plurality of arms 32 at positions adjacent each end and adjacent each side of the door opening, being arranged in the same relation longitudinally on the shaft but extending in different directions radially. Between the arms 32 are mounted the arms 33, 35 the arms 32 and 33 being clearly illustrated in detail in Figs. 4 and 5. The lower end of the arm 32 is formed with outwardly extending flanges 34 and a right angular groove 35. Bolts 36 secure a strap member 36' to the 40 flanges 34, the strap being formed with a right angular groove that combines with the angular groove 35 to form a square opening which provides the means for mounting the arm 32 upon the shaft 8 by tightening the 45 screws 36' and drawing the strap 36 to tightly embrace the shaft 8 in the square opening. The arm 32 extends outwardly in a line substantially at right angles to the flanges 34.

The arm 33 is slightly varied in form to 50 that of the arm 32 in that it extends outwardly on a line which is substantially 45° to the flanges 34, the object of which is to provide three arms through an arc of 90°. Both arms 32 and 33 are bifurcated as at 39 55 to support levers 40 which in turn support the curved angularly arranged blades 37. The levers 40 are pivotally mounted in the bifurcation 39 as at 41 and extend beyond the bifurcation to give purchase or leverage 60 65 whereby the spring 42 contained in the groove

43 when connected to the pin 44 and the end of the lever 39 as at 45 will move the lever 40 until the blades 37 contact with the inner wall of the mixer.

The arms are arranged on the shaft so that 70 the arms 32 are adjacent the ends of the mixer and the door opening and an arm 33 is attached between each pair of arms 32. In the drawings there is illustrated a separate set on each side of the door, the sets on opposite sides of the door being mounted on opposite sides of the shaft and having the blades 37 inclined at opposite angles. The arms project radially from the shaft 8 at an angle of 45° to each other and therefore 75 the blades 37 combine and have like effect of an Archimedean screw. The blades being oppositely inclined on opposite sides of the door has the effect of two oppositely directed Archimedean screws which tend to 80 propel the mixing materials back and forth in the mixer. The blades being arranged thus throw the material against the door and when the door has been opened the blades will empty the mixer by continuing the rotation 85 thereof.

Although a specific embodiment of the present invention has been illustrated and described it is to be understood that various alterations may be made in the details of 90 construction without departing from the spirit of the invention as defined by the scope of the appended claims.

What I claim is:—

1. In a mixing machine, side and end members forming an enclosure open at its top and bottom, parallel retaining members attached to the lower edges of said side members, one of said retaining members being detachable, a bottom member at the bottom of said enclosure between said retaining members and abutting said retaining members, and a supporting member on which said bottom member rests, said supporting member being spaced from said detachable retaining member to permit withdrawal of the bottom member in a direction transverse of said enclosure, on removal of said detachable retaining member.

2. In a mixing machine, side and end members forming an enclosure open at its top and bottom, supporting means at the lower edges of said end members, parallel retaining members attached to the lower edges of said side members, one of said retaining members being detachable, a concave bottom member at the bottom of said enclosure between said retaining members and abutting said retaining members, said bottom member having its ends closed by said supporting means, a supporting member on which said bottom member rests, said supporting member being spaced from said detachable retaining member and said supporting means being spaced apart to permit with- 115 120 125 130

drawal of the bottom member in a direction transverse of said enclosure, on removal of said detachable retaining member.

3. In a mixing machine, side and end mem-

bers forming an enclosure open at its top and bottom, parallel retaining members attached to the lower edges of said side members, and retracted outwardly from the inner walls of said side members, one of said retaining members being detachable, a bottom member at the bottom of said enclosure between said retaining members and in engagement therewith and abutting upwardly against said side members, and a supporting member on which said bottom member rests, said supporting member being spaced from said detachable retaining member to permit withdrawal of the bottom member in a direction transverse of said enclosure, on removal of said detachable retaining member.

4. In a mixing machine, side and end mem- bers forming an enclosure open at its top and bottom, parallel retaining members at-

tached to the lower edges of said side mem- bers, one of said retaining members being de- tachable, and the other retaining member having a curved frame portion adapted to define a door opening, a curved bottom mem- ber at the bottom of said enclosure resting partly on the last named retaining member and engaged outwardly by said detachable retaining member, and a supporting member on which said bottom member rests, said sup-

porting member being spaced from said de- tachable retaining member to permit with- drawal of the bottom member in a direction transverse of said enclosure, on removal of said detachable retaining member.

40 5. In a mixing machine, side and end mem- bers forming an enclosure open at its top and bottom, parallel retaining members at-

tached to the lower edges of said side mem- bers, one of said retaining members being de- tachable, a bottom member at the bottom of said enclosure between said retaining mem- bers and abutting said retaining members, and a detachable supporting member on which said bottom member rests, whereby

50 said bottom member may be removed by de- tachment of said supporting member and the detachable retaining member.

6. In a mixing machine, side and end mem- bers forming an enclosure open at its top

55 and bottom, supporting means at the lower edges of said end members, parallel retaining members attached to the lower edges of said side members, a concave bottom member at the bottom of said enclosure between said re-

60 taining members and abutting said retaining members, said bottom member having its ends closed by said supporting means, a support- ing member on which said bottom member rests, the supporting means at one end of

65 said bottom member being detachable, where-

by said bottom member may be withdrawn lengthwise after removal of the detachable supporting means.

In testimony whereof I affix my signature.

FRANCIS JOHNSON.
